(57) **CLAIM**

I claim the ornamental design for a masonry retaining wall block, as shown and described.

DESCRIPTION

FIG. 1 is a perspective view of a retaining wall block showing my new design;

FIG. 2 is a top view of the retaining wall block of FIG. 1;
FIG. 3 is a side view of the retaining wall block of FIG. 1; and,
FIG. 4 is an underside view of the retaining wall block of FIG.
1.

The broken lines in the drawings represent unclaimed portions of the retaining wall block and form no part thereof.
